(57) **CLAIM**

The ornamental design for a cleaning robot, as shown and described.

DESCRIPTION

The patent or application file contains at least one drawing executed in color. Copies of this patent or patent application publication with color drawing(s) will be provided by the Office upon request and payment of the necessary fee.

1.1 is a front view of a first cleaning robot, showing the new design;

1.2 is a rear view thereof;

1.3 is a left view thereof;

1.4 is a right view thereof;

1.5 is a top view thereof;

1.6 is a bottom view thereof;

1.7 is a front perspective view thereof;

1.8 is another front perspective view thereof;

1.9 is a rear perspective view thereof.

2.1 is a front view of a second cleaning robot, showing the new design;

2.2 is a rear view thereof;

2.3 is a left view thereof;

2.4 is a right view thereof;

2.5 is a top view thereof;

(Continued)

2.6 is a bottom view thereof;
 2.7 is a front perspective view thereof;
 2.8 is another front perspective view thereof; and
 2.9 is a rear perspective view thereof.
 The portions of the cleaning robot shown in yellow form no part of the claimed design.
